UNITED STATES PATENT OFFICE.

JOHN BROWN HARRIS, OF NASHVILLE, TENNESSEE.

SMOKE-CONSUMING FURNACE.

SPECIFICATION forming part of Letters Patent No. 784,324, dated March 7, 1905.

Application filed October 21, 1904. Serial No. 229,398.

To all whom it may concern:

Be it known that I, JOHN BROWN HARRIS, a citizen of the United States, and a resident of Nashville, in the county of Davidson and State 5 of Tennessee, have invented a new and Improved Smoke-Consuming Furnace, of which the following is a full, clear, and exact description.

The invention relates to smoke-consuming 10 furnaces, such as shown and described in the Letters Patent of the United States No. 754,999, granted to me March 22, 1904.

The object of the present invention is to 15 provide a new and improved smoke-consuming furnace arranged to cause a reduction of the volume of nitrogen in the fire-box by the introduction of minute jets of steam, to deflect the rising gases and smoke in the fire-box, to bring the same near the air-inlet ports 20 for mixture with the air drawn in by the action of the steam-jets, and to insure a more ready and complete combustion of the mixture.

The invention consists of novel features and 25 parts and combinations of the same, as will be more fully described hereinafter and then pointed out in the claims.

A practical embodiment of the invention is represented in the accompanying drawings, 30 forming a part of this specification, in which similar characters of reference indicate corresponding parts in all the views.

Figure 1 is a longitudinal sectional elevation of the improvement on the line 1 1 of 35 Fig. 2. Fig. 2 is a transverse section of the same on the line 2 2 of Fig. 1. Fig. 3 is a like view of the same on the line 3 3 of Fig. 1. Fig. 4 is a perspective view of the steam-jet pipe, and Fig. 5 is a plan view of a modified form of the steam-jet pipe.

The boiler A is set in the usual manner in a brickwork B, containing a fire-box C, having a grate D, below which is arranged an ash-pit E, having in its floor a cemented wa- 45 ter-pit E' containing water, which in evaporating forms wet steam, drawn by the draft up through the burning fuel, so as to be dissociated into its elements, taking up carbon and forming water-gas and, in general, to aid

in the combustion of all the gases. Access is 50 had to the ash-pit E and to the fire-box C by suitable doors E² and C'. At the rear end of the fire-box C is arranged a bridge-wall F, having its top in inverted arch shape and spaced from the under side of the boiler A to 55 form a combustion-chamber G, the rear end of which leads to the rear end of the boiler A for heated gases to pass in and through the flues of the boiler A in a forward direction and to finally pass into a stack A'.

In the front upper portion of the fire-box C is arranged an air-chamber H, formed by spaced concentric arches H' and H'', extending from the side walls of the brickwork B, the top of the outer arch H' being spaced 65 from the under side of the boiler A to leave the latter unobstructed at this point, and thus maintain a full heating-surface of the boiler throughout the length thereof. The lower arch H'' extends above the door C', so as not 70 to obstruct the entrance of the fire-box C. In the air-chamber H are arranged air-retarding devices, preferably in the shape of checker-bricks H³, to retard the air in the said chamber H to insure heating thereof to a high de- 75 gree previous to the heated air passing into the fire-box above the burning fuel on the grate D. The inner end of the upper arch H' projects a distance beyond the inner end of the lower arch H'', so that the heated air passing from the chamber H at the inner open end is guided toward the combustion-chamber G, as will be readily understood by reference to the arrow shown in Fig. 1.

The sides of the air-chamber H, at the front 85 end thereof, are connected with air-ducts I, extending rearwardly in the side walls of the brickwork B to lead to the outer air at the back wall of the brickwork, and the rear ends of the said ducts I are adapted to be opened and 90 closed by suitable hinged doors J, each connected by a chain J' with a bell-crank lever J'', fulcrumed on the top of the brickwork B and connected by a link J³ with another bell-crank lever, J⁴, arranged on the front of the 95 brickwork B, and this bell-crank lever J⁴ is provided with a depending handled chain or rope J⁵ under the control of the operator.

Thus upon pulling the chains J^5 the doors J are swung open, so as to allow air to pass through the ducts I into the heating-chamber H and from the latter into the fire-box, it being understood that the air during its passage through the ducts I receives a preliminary heating, and this heated air is heated to a very high degree in the chamber H before it passes into the fire-box C .

10 In the chamber H extends a transverse stem-jet pipe H^4 , connected by a valved pipe H^5 with the steam-dome A^2 of the boiler or other source of steam-supply. The pipe H^5 is arched to follow the contour of the chamber H , and the said pipe is provided on its forward portion with perforations for the escape of the steam in minute jets. The pipe H^4 is in transverse alignment with the entrances of the air-ducts I , so that the steam passing in 15 jets into the chamber H also serves to draw in air through the air-ducts I . The steam-jet pipe H^4 may be located outside of the chamber H , and in this case the said pipe H^4 is provided with branch pipes H^6 , (see Fig. 5,) 20 extending into the chamber H to discharge steam into the latter in a forward direction, the same as the perforated pipe H^4 , previously mentioned.

25 A second air-chamber K is formed in the arched wall F , and this chamber leads to the inverted arched top of the bridge-wall, and on this top are arranged longitudinally-extending bricks K' , spaced apart to form openings K^2 for the air to pass from the chamber K 30 through the said openings into the combustion-chamber G . (See Fig. 3.) To the bottom of the chamber K leads a door K^3 from the ash-pit E for the convenient removal of ashes and cinders that may fall into the chamber K through the openings K^2 . From the 35 uppermost bricks K' extend baffle-plates K^4 , extending from the side walls of the brick-work to the sides of the boiler A and to the top of the chamber G , so that the smoke and gases are deflected downwardly to pass under the baffles to be set afame by the hot air from the openings K^2 , leading from the chamber K . Into the chamber K also open the forward ends of air-ducts L , built on the inner face of 40 the side walls of the brickwork B , and the rear ends of the said ducts L connect by branch ducts L' in the back wall of the brickwork B with ducts L^2 , extending forwardly in the side walls of the said brickwork B . The forward 45 ends of the ducts L^2 are adapted to be opened and closed by doors N , similar to the doors J , and under the control of the operator by the employment of chains or ropes N' , each of which is attached at one end to a corresponding 50 door and then extends upward over a pulley N^2 , journaled on the top of the brickwork B . The depending front end of the chain or rope N' is adapted to be taken hold of by the operator, so that the latter on pulling the rope 55 swings the corresponding door N into an open

position to allow atmospheric air to pass into the front end of the duct L^2 to travel rearwardly therein and to finally pass by the branch duct L' into the duct L to finally reach the air-chamber K in the bridge-wall F . It will 60 be seen that the air in its rearward and forward passage in the ducts L^2 L' L receives a preliminary heating and a final heating to a high degree in the chamber K to pass in this condition through the openings K^2 into the combustion-chamber G . In the latter are arranged checker-bricks O to somewhat retard the rearward flow of the smoke and gases and to cause a thorough intermingling of the air with the gases to insure complete combustion. As 65 indicated in Fig. 1, at the front end the checker-bricks O are set in step form, so that the air and gas are caused to travel in an upward direction toward the under side of the boiler A to thoroughly heat the same. 70

75 From the foregoing it will be seen that when the fuel is burning on the grate D and the doors J and N are opened then air passes through the ducts I and L^2 L' L into the air-chambers H and K . The air in the chamber H is heated and mixed with the steam issuing in jets from the pipe H^4 , and this mixture of heated air and steam passes directly into the smoke and gases arising from the burning fuel on the grate D , so as to insure a complete 80 combustion of the gases and a reduction of the smoke. The mixture in passing over the bridge-wall comes in contact with a fresh supply of highly-heated air from the chamber K , and this air is thoroughly mixed with the smoke and gases in the combustion-chamber G , especially by the aid of the checker-bricks O , to insure a complete combustion previous to the heated gases leaving the combustion-chamber and passing through the boiler A 85 into the smoke-stack A' . 90

95 It is understood that by the use of steam in the chamber H the air is readily drawn into the chamber H from the ducts L , and the steam causes a reduction of the volume of nitrogen 100 in the fire-box and the formation of water-gas by the decomposition of the steam.

105 Having thus described my invention, I claim as new and desire to secure by Letters Patent—

110 1. A smoke-consuming furnace, comprising a fire-box, an independent air-chamber at the front of the furnace and upper part of the fire-box, the bottom of which forms the top of said fire-box, means for delivering heated air to said air-chamber, and thence to the combustion-chamber within the fire-box, and means for introducing steam to the air-chamber at the front thereof, to commingle with the heated air therein before the passing of this 115 air to the combustion-chamber. 120

125 2. A smoke-consuming furnace, comprising a fire-box, an independent air-chamber at the front of the furnace and upper part of the fire-box, the bottom of which forms the top of said 130

fire-box, means for delivering heated air to said air-chamber, and thence to the combustion-chamber within the fire-box, and a pipe connecting with a source of steam and having 5 a transverse perforated pipe for introducing steam to the air-chamber at the front thereof, as and for the purpose set forth.

In testimony whereof I have signed my name to this specification in the presence of two subscribing witnesses.

JOHN BROWN HARRIS.
